CLAIM

I claim the ornamental design for an information handling system bezel, as shown and described.

DESCRIPTION

FIG. 1 is a front perspective view of the information handling system bezel comprising the present invention; FIG. 2 is a front elevation view thereof; FIG. 3 is a rear elevation view thereof; FIG. 4 is a right side view thereof; FIG. 5 is a left side view thereof; FIG. 6 is a top view thereof; FIG. 7 is a bottom view thereof; FIG. 8 is a bottom perspective view thereof; FIG. 9 is an upper front perspective environmental view thereof; and, FIG. 10 is a detailed view thereof as identified in FIG. 9. Broken lines shown in the drawings illustrate portions of the information handling system bezel, and form no part of the claimed design. The broken lines showing the rest of the information handling system in FIG. 9 illustrate environment and form no part of the claimed design. The broken lines in FIG. 10 are boundaries of the enlarged view and form no part thereof.
